UNITED STATES PATENT OFFICE

HOBART M. LOCKHART, OF NORTH WILKESBORO, NORTH CAROLINA

PUMP

Application filed December 5, 1930. Serial No. 500,383.

This invention relates to certain new and useful improvements in pumps having more particular reference to a deep well pump for supplying water from the pump to city houses and the like, and the primary object of the invention is to provide an improved pump head for apparatus for operating the pump.

The nature and advantages of the apparatus are apparent to those skilled in the art in the light of the following explanation of the drawings wherein is shown a preferred embodiment of the invention.

A salient feature of the present invention is to provide an improved pump head which may be readily dismantled and just as readily assembled, facilitating removal of any of the working parts of the same for the purpose of repair or for any other reason.

A still further object of the invention is to provide a pump head, wherein the gearing forming part thereof is always immersed in a suitable lubricant, and further, wherein the head may be driven from an electric motor of one quarter horse power, and yet deliver at least two gallons of fresh water each minute.

A further object of the invention is to provide a pump head that is very simple in construction, consists of but few parts, and which upon the opening of a spigot arranged in the water line, the pump will be set into operation for delivering fresh water.

Other objects and advantages of the invention will become apparent during a study of the following description, taken in connection with the accompanying drawings wherein:

Figure 1 is an elevational view of the invention looking at one side thereof,

Figure 2 is a similar view in the opposite side thereof.

Figure 3 is a top plan view of the gear casing, the top section of the same being removed.

Figure 4 is a longitudinal sectional view therethrough taken substantially on the line 4-4 of Figure 3 with the motor removed.

Figure 5 is an end elevational view of the invention.

Figure 6 is a view partly in section and partly in elevation for more clearly illustrat-

ing the automatic switch arranged in circuit with the electric motor.

Referring in detail to the drawings, it will be seen that the improved pump head comprises a gear casing 1 within which is journaled a transverse shaft 2 and opposite walls of the gear case are provided with apertures 3 providing bearings for the ends of the shaft. Splined to the shaft 2 is a relatively large gear 4 that is in mesh with a pinion 5 splined to a second transverse shaft 6, the said walls of the casing being provided with apertures 7 constituting bearings for the end of the shaft 6. Also splined on the shaft 6, is a relatively large gear wheel 8 that is in mesh with a pinion 9 splined to a driven shaft 10, the said walls of the gear casing 1 being provided with apertures 11 constituting bearings for the ends of the driven shaft 10.

In order that the shafts 2, 6 and 10, may be readily removed from the gear case, I prefer to form the gear case into two pieces by dividing the same along its horizontal plane, taken longitudinally of the case and near the center of the several apertures therein.

The line of division extends from one end to the other of the gear case and thus divides the same into a lower section A and an upper or cover section B. The lower section A at the end thereof is provided with suitably apertured flanges 13 to facilitate anchoring of the section to a suitable support.

Exteriorly of the gear case, the driven shaft 10 on one end thereof is equipped with a pulley wheel 14 over which is trained a drive belt 15, the latter being also trained over a relatively small pulley wheel 16 on one end of the shaft 17 of a suitable electric motor M.

Exteriorly of the gear case, on one end of shaft 2, is a crank arm 18 and a connecting rod 19 at one end is pivoted as at 20 to a crank pin extending laterally from one end of the crank arm 18. The other end of the connecting rod 19 is pivoted to a pin 21 projecting laterally from the upper end of a slide member 22 that is slidable on a guide rod 23 depending from the gear case 1. The guide rod 23 is braced with respect to the casing 1 through the medium of a suitable brace 24.

Bolted to the lower end of the guide rod 100

23 at 25 is a stuffing box 26. The stuffing box 26 is on the upper end of pump tubing 27. Operable within the pump tubing 27, and stuffing box 26 is the usual pump or sucker rod 28 that is secured to suitable means 29 to a lateral lug 30 integral with the slide 22.

Manifestly, upon operation of motor M, the 10 rotative movement of the shaft 17 of the motor is transmitted to the driven shaft 10, rotative movement of the shaft 10 being transmitted to the shaft due through the medium of the gearing arranged within the gear case 1. The crank arm 18 rotating with the shaft 2 imparts an oscillatory movement to the connecting rod 19 thus imparting reciprocatory movement to the slide 22, the latter transmitting its movement to the sucker rod or pump rod 28 for forcing water from the well upwardly through the well tubing 27 and 20 stuffing box 26 to discharge from the stuffing box through a lateral outlet nipple 32 extending laterally from the stuffing box.

On the outer end of the nipple 31 is a riser 32 connected to the nipple through a suitable 25 elbow 33 arranged within the riser 32 is a check valve 34 and above the check valve a T-coupling 35. Leading from a branch of the T-coupling 35 is a branch pipe 36 that at its outer end is coupled through the medium of elbow 37 with a supply pipe 38 adapted to 30 lead through any suitable water main for supplying a house or the like with water.

On the riser 32, above the T-coupling 35 is an air chamber 39 that has a nipple 40 rising 35 from the top thereof. Threadedly engaged with the upper end of the nipple 40 is a valve casing 41 within which is arranged an automatic valve structure.

The automatic switch structure arranged 40 in the casing 41 comprises a pair of contacts 42 respectively anchored at one end to a wall of the casing as at 43 suitably insulated from said wall as at 44. The confronting ends of the fixed contact 42 are arranged in spaced 45 relation, and are adapted to be bridged by a bridge member 45 that includes a vertical stem 46 the free end of which is suitably engaged with a diaphragm 47 anchored within the bottom of the casing as at 48. The bridge member 45 is normally maintained in contact with the adjacent end of the fixed contact members 42 through the medium of a coil spring 49 impinging against said member 45. Secured to the upper end of the coil spring 50 is a plug 50 threadedly engaged with the top wall of the casing 41.

The switch structure arranged in the casing 41, as just described, is in a closed condition when the electric motor M is running, 60 said switch being arranged in circuit with the electric motor. When the air pressure in the chamber 39 exceeds a predetermined amount, the pressure consequently exerted on the diaphragm 47 will overcome the action 65 of the spring 49 thus moving the bridge mem-

ber 45 out of engagement with the contact 42 opening the circuit to the motor M for stopping the same, resulting in a stopping of the pump.

When a spigot or the like is turned on for 70 drawing water from the pump the air pressure is of course decreased, thus permitting the bridge member 45 under influence of the spring 49 to move downwardly to bridge the contact 42 thus closing the circuit to the motor for starting the same whereby the pump is again put in motion as is apparent.

The removal part or cover part B of gear casing 1 is secured to the fixed or lower part 75 A of the gear casing through the medium of suitable bolts 51.

The slide 22 adjacent its upper end is also provided with a suitable grease cup 52 for 80 maintaining the slide and the guide rods 33 therefor in a well lubricated condition.

From the foregoing then it will be seen that I have provided a working head of this character, which will as before stated permit the removal of certain of the working parts, 90 without requiring a removal of other of the working parts, and that the movable parts of the working head especially the gearing, and the slide 22 are maintained at all times in a well lubricated condition, it being understood that the casing 1 is adapted to contain 95 a suitable lubricant, and that further the working head is capable of operation free of such noise incident to the operation of such pump.

Even though I have herein shown and 100 described the preferred embodiment of the invention it is to be understood that the same is susceptible to changes, modifications and improvements coming within the scope of the 105 appended claim.

Having thus described my invention, what I claim as new is:

In combination with a pump and transmission mechanism including a casing, a vertically arranged rod having its upper end connected with the casing and its lower end with the pump, a brace connected with the casing at that side which is opposite to the side to which the rod is connected, said brace extending diagonally and having its lower end connected with the lower end of the rod, a cross head slidably arranged on the rod and having a projection at its upper end and a projection at its lower end, means for connecting the piston rod of the pump to the lower projection, a pitman connected to the upper projection and to the transmission means.

In testimony whereof I affix my signature. 110
HOBART M. LOCKHART. 125
